UNITED STATES PATENT OFFICE.

EZEKIEL WHEELER, OF KINGFISHER, OKLAHOMA TERRITORY.

METAL POST FOR WIRE FENCES.

SPECIFICATION forming part of Letters Patent No. 687,093, dated November 19, 1901.

Application filed June 6, 1901. Serial No. 63,359. (No model.)

To all whom it may concern:

Be it known that I, EZEKIEL WHEELER, a citizen of the United States, residing at Kingfisher, in the county of Kingfisher, Territory 5 of Oklahoma, have invented certain new and useful Improvements in Metal Posts for Wire Fences, of which the following is a specification.

My invention is directed to a construction 10 of metal fence-post and the way in which it is erected in the post-hole, whereby the cost to the farmer in erecting a wire fence is greatly lessened, the work readily done, and the fence rendered durable.

15 The features of construction which embody what is new will be specifically set out in the claim appended hereto, in connection with the accompanying drawings, in which—

Figure 1 shows a panel of a wire fence as 20 it is erected with metal posts in accordance with my improvement. Fig. 2 shows one of the metal posts in perspective. Fig. 3 shows enlarged, in side view, one of the metal posts and the provision whereby it is centered and 25 held erect in the post-hole preparatory to filling the hole with cement. Fig. 4 shows the lower part of one of the metal posts as it is first centered erect in the post-hole and then secured by cement in a plastic condition. Fig. 30 5 shows views of the way in which the line-wire is secured to the post and how the wires with their barbs may, in being stretched, be drawn through the post. Fig. 6 shows the centering stand-block for the post, having a circular mortise. Fig. 7 is a stand-block having 35 a rectangular mortise.

In erecting the fence the post-holes are first dug each of equal depth and of a width to contain a body of cement that will harden in 40 the post-hole around the post. For this purpose the post 1 may be held central in the hole by hand while filling in the cement or be driven in the bottom of the hole; but I prefer to use a centering stand-block 2, laid in 45 the bottom of the post-hole, and to center the post by seating its pointed end into a mortise 3 in the block, which thereby serves also to hold the post in a vertical position preparatory to filling the post-hole with cement 4, so that 50 the post when set has a true and firm mounting. In this way a line of metal posts can be

erected quickly and in a short time become firmly planted ready to receive the line-wires.

I find the less expensive Louisville cement mixed with sand and filling the post-hole with 55 a body of considerable thickness around the post will when it becomes dry form a support for the post of sufficient firmness to resist the strain of the line-wires due to force caused by their contraction.

The post is a flat bar of a length suited to the number of line-wires it is intended to use, its width about two inches and about one-half inch thick, and is tapered to form a point adapted to be seated into a mortise in the centering stand-block, whereby the post is both centered and held erect in the post-hole at a depth therein of about two and one-half feet. This tapered part has a mortise 5 in its flat side, and when the post-hole is filled with cement it runs through this mortise just below the surface of the ground, and becoming set and hard forms a bar through the post and locks it to the center of the cement body. This cement bar in its locking function on 75 the post is reinforced by the interlocking of the point of the post with the centering stand-block, and the cement embedded at these two points is a very advantageous feature of my improvement, because it enhances the firm 80 setting of the post. The line of posts being thus erected and firmly set, the line-wires 6 are strung and stretched along the edges of the posts from one end of the line to the other and then engaged with each post. For this 85 purpose each post is formed with mortises 7, corresponding with the number of line-wires. Meditately of their length these mortises are intersected by slits 8, made obliquely across the edge of the post, so that the line-wires 90 being inserted through these oblique slits are by reason of the oblique standing of the edge slits to the horizontal wires prevented from working out of the mortises. The mortises stand vertically along the edge of the post, 95 and the inner wall 9 of the mortise below the oblique edge slit may be oblique inward from the bottom of the mortise to the slit. The effect of this inclined wall is to hold the line-wire down on the bottom of the mortise, as in 100 Fig. 3. The inner wall 10 of the mortise above the oblique slit may also extend obliquely up-

ward from the oblique slit to the top of the mortise, and these oblique inner walls increase the thickness, and thereby the strength, of the slotted edge parts.

5 To keep the line-wires taut, it is often necessary to take up the slack caused by expansion, and it is for this purpose that the line-wires are confined in mortises to give freedom to easily pull the wire through comparatively 10 large openings, and these mortises also have the important advantage of allowing barbs 11 on the line-wires to be drawn through the posts in the event of the barbs being near the posts when stretching the wires, as in Fig. 1, 15 or should the slack in the wires be sufficient to draw the barbs from one side of the post to the other in tightening the wire.

While the oblong form of the mortise facilitates the passage of two pronged barbs 20 through it, as in Fig. 5, a groove 12 may be formed across the back wall of the mortise opposite the oblique slit to facilitate the passage through it of barbs having a greater number of prongs, as seen in said figure. This 25 provision for drawing the barbs through the post avoids the difficulty and trouble of pulling the wires from their connection with the post, as it would be often found necessary in taking up considerable slack in the wires, the 30 barbs usually being about six inches apart.

Notwithstanding the mortises prevent any binding of the wires in the posts in the operation of tightening the wires, yet the friction of the wires in the posts would necessarily produce considerable strain on the post in the direction of the pulling force on the wires. 35 As a means whereby the post may be braced against such strain it is formed with a lug 13 at its upper end on each side, so that a prop 40 14, (shown in dotted lines in Fig. 1,) placed against the lug and driven into the ground, will resist the strain upon the post caused by tightening the wires. This prop can be used on either side of the post as may be required 45 in tightening the wires from either end of the fence, and it will be understood that such line-tightening is usually done between posts.

For reinforcing the seating and holding of the post in the stand-block lugs 15 15 may 50 be formed on the taper end of the post between its end and the mortise 5, so that in the seating of the post these lugs rest on the block and coöperate with the post-mortise 5, the mortise in the block, and with the cement 55 filling in the post-hole to give a firm centering-support to the post, as seen in Figs. 3 and 4.

The centering stand-block is preferably of wood, but may be of iron, with a collar 2' around its centering-mortise, as in Fig. 7. If 60 of wood, the thickness of the block should be sufficient to form a socket deep enough to give its walls a hold upon the angular point of the post, so that it stands erect and needs no one to hold it while the post-hole is being 65 filled with cement; but the stand-plate may

also have the function of an anchor to the post, and for this purpose the point of the post may be formed with a projection or shoulder 16 and the stand-plate with a circular mortise formed with a notch 17 to receive the 70 post projection and allow it to pass through and below the mortise and then to be turned to its proper seat, thereby engaging the post projection with the under side of the stand-plate, locking the post down as well as in a 75 vertical position, as in Figs. 1, 2, and 6.

Obviously the erection of the posts in post-holes and subsequently filling the holes with plastic cement to harden around the posts is better, cheaper, and more durable and gives 80 greater firmness to the post than is possible with a post having a hard molded base on it and which for protection against breakage must be provided with a metal casing or jacket.

Should the filling of the post-hole with the 85 plastic cement put the post out of true vertical position, it can be pushed to correct any incline before the cement hardens.

One advantage of enlarging the bases of the 90 mortises is to form a hold for the wires without necessarily making the slits in the edge of the post oblique to the edge of the post.

Obviously a key of plastic cement run through the mortise in the post, so that it forms a part of the plastic cement poured 95 around the post at the time of setting it, renders the key a permanent part of the fixed body of the cement setting and is a very cheap way of forming a permanent anchorage for the post that cannot be obtained by 100 anchors embedded in the earth.

A fence which the farmer with the aid of a farm hand can erect cheaply and quickly and with posts obtained in the trade is a big gain in erecting fencing, and the planting of posts 105 so that they are permanent by the use of plastic cement is a new conception in obtaining permanently-set posts.

Referring to Figs. 3 and 4, it will be noted that the aperture in the base-block is tapered, 110 the walls flaring upward, and that these walls form seats for the taper end of the post between the shoulders. This construction gives a seating for the post which reinforces the shoulders 115 in preventing the breaking and separation of the cement lock in the mortise 5 from the plastic body which is poured into the post-hole and hardens around the flat tapered end of the post. This cement lock is like that which would result in a very effective degree like a metal strap passed through the mortise and fastened at each end to the base-block on each side of the post. It is also important to note that as the post is a single flat bar this cement lock extends 120 solidly through the bar and forms a solid part therewith.

I claim—

In a fence-post and in combination with a base-block having a tapered aperture en- 130

larged at one side, a post consisting of a single flat bar having a tapered lower end, shoulders one at the end and one above the end adapted to engage the under and the upper side of said block and a mortise above the shoulders through which a cement key in plastic form passes as an integral part of the plastic cement base, whereby the post is

locked and centered within and to the body 10 of the plastic cement above the base-block.

In testimony whereof I affix my signature in presence of two witnesses.

EZEKIEL WHEELER.
